ELECTRICAL TREATING APPARATUS, ESPECIALLY FOR STERILIZATION

Franklin S. Smith, New Haven, Conn.

Application October 8, 1934, Serial No. 747,441

50 Claims. (Cl. 21—102)

This invention relates to the treatment of materials and especially to the electrical sterilization of particularly food products and more particularly to the destruction electrically of insect life, such as the pupae, larvae, eggs, and the like, therein.

One of the objects of this invention is to provide an efficient and dependable apparatus which is particularly adapted for achieving the electrical sterilization of products, such as cereals, flour, and the like, and for effectively destroying therein such insect life as such products are frequently infested with, taking the form usually of eggs, larvae, pupae, and the like. Another object is to provide an apparatus of the above-mentioned character in which, in particular, packaged products may be dependably treated or sterilized and in which, moreover, the effects of the dielectrics constituting the cartons or packages, tending in certain physical relations to oppose uniform sterilization of the contents, may be effectively and, moreover, in a simple and dependable manner, overcome. Another object is to provide an apparatus of the above-mentioned character a simpler and less expensive, but nevertheless efficiently acting, electrode construction and, moreover, one that will be well adapted to ready and quick replacement, capable of substantially entirely avoiding the effects of air currents or rarefactions of air, due to the movement of the electrode, and capable, also, of rapid and inexpensive manufacture. Another object is to provide an electrode construction that will be well adapted for long-continued use and in which also efficient and simple cooling action may be dependably achieved.

Another object is to provide, in an apparatus of the above-mentioned character, a conveyor means or system better adapted particularly to the handling of bulky packages or cartons and adapted, furthermore, to take part in a unique, simple, and thoroughly practical way, in the achievement of the desired electrical sterilizing action. Another object is to provide such a conveyor means that will be of inexpensive construction, thoroughly dependable and reliable in action and having component parts which, though they may take part in the control or achievement of the electrical discharge, may nevertheless be embodied in inexpensive form, may be quickly and inexpensively assembled, and likewise replaced when and if necessary. Another object is to provide a sterilizing apparatus of the above-mentioned character that will be well adapted to meet certain peculiar and widely varying condi-

tions of practical use. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of my invention,

Figure 1 is a front elevation of the apparatus, certain parts of the housing proper being broken away to show certain features more clearly and certain parts within the housing being likewise broken away to show other parts more clearly;

Figure 2 is a plan view of the apparatus, as seen from above in Figure 1;

Figure 3 is a transverse vertical sectional view, certain parts being omitted, as seen along the line 3—3 of Figure 2;

Figure 4 is a vertical sectional view, as seen along the line 4—4 of Figure 1, certain parts being omitted;

Figure 5 is a front elevation of a double electrode mounting and drives therefor, on an enlarged scale, one of the electrodes and its drive being shown in central vertical cross-section;

Figure 6 is a side elevation, as seen along the line 6—6 of Figure 5, of one of the electrodes and its drive;

Figure 7 is a diagrammatic representation of the relation of one electrode, to the packaged product and its action thereon;

Figure 8 is a view like that of Figure 7 but showing the reversed action on the packaged product of another or a companion electrode.

Similar reference characters refer to similar parts throughout the several views in the drawings.

Referring now first to Figures 1 and 2, I have there shown a casing or housing, generally indicated at 10, within which certain parts of my apparatus are enclosed and by which certain other parts may be supported, the housing being preferably built up of sheet metal and a suitable framework and being in general not unlike that disclosed in my co-pending application Serial No. 627,291, filed August 2, 1932, issued October 9, 1934, as Patent No. 1,975,805, to which reference may be made for further details. In the right-hand wall 10a of the housing 10 is provided a suitable aperture through which and onto a suitable chute or slide 11 the products to be sterilized usually or illustratively packaged food prod-

ucts, may be injected onto a conveyor means, to be more clearly described hereinafter, and comprising preferably three sections generally indicated in Figures 1 and 2 at A, B and C, whereby the products or packages, are moved from the right, as viewed in Figure 1, toward the left, interiorly of the housing 10, being discharged from the latter by way of a chute, or the like, 12 appropriately related to the left-hand end of the conveyor means A, B, C and to a suitable opening in the left-hand end wall 10^b of the housing 10.

The conveyor means A, B, C is appropriately supported within the housing 10, preferably resting upon and suitably secured to the bottom 10^c of the housing 10 and it extends, as will now be clear, from one end wall 10^a to the other end wall 10^b. It includes certain driven roller members, the roller members of sections A and C being preferably of identical construction whereas the roller members of the central or intermediate section B, falling within the sterilizing or treatment zone or zones, as will be presently made clearer, are of identical construction but different from the construction of the rollers of the sections A and C, being also of greater length transversely of the apparatus (see Figure 2) than are the rollers of sections A and C of the conveyor. The rear ends of all of the rollers, however, are preferably aligned and find support in the same side frame structure.

Accordingly, I provide a side frame structure or beam 13 (Figure 1, 2, 3 and 4), the member 13 being preferably made of solid dielectric material, such as laminated "bakelite", or the like, and being preferably of unitary construction throughout its length thereof, of course, it may be built up in any suitable or appropriate manner; at its right-hand end (Figure 1) it is provided with a downward extension 13^a, forming a sort of leg which is bolted or otherwise secured to a suitable upright or standard 14 secured to the right-hand end of the bottom or floor 10^c of the housing 10, and at its left-hand end (Figure 1) it is likewise provided with a downward extension or leg portion 13^b which is bolted or otherwise secured to the standard 15 which, like the standard 14, rests upon and is secured to the floor 10^c of the housing 10 and extends crosswise of the latter.

At closely spaced intervals along the uppermost longitudinal and horizontally extending edge of the side frame or beam 13, the latter supports or has suitably secured thereto a series of bearings 16, preferably of the so-called "oil-less" type made, for example, of oil-impregnated wood. As is better shown in Figures 3 and 4, this upper edge of the beam 13 may be recessed for each bearing 16 which may be set into such a recess and secured in place in any suitable way.

Illustratively I may provide, for section A, twelve such bearings 16, for section B of the conveyor means I may provide sixteen such bearings 16, and for section C, generally similar in construction to section A, I may likewise provide twelve such bearings 16, it being now clear that the side frame or beam 13 is common to and extends throughout all of the three conveyor sections A, B and C.

Laterally juxtaposed to that portion of the frame 13 that extends throughout section A (see Figures 1 and 2) I provide a side frame or cantilever-like member 17, also made preferably of solid dielectric material, such as laminated "bakelite", and provided at its right-hand portion with a downwardly directed extension or leg 17^a

which is secured as by bolts or screws to the other side face of the standard 14, member 17 being thereby positioned in parallelism to the side frame 13 and with its upper edge aligned with the upper edge of the member 13. The upper edge of the side frame member 17 is provided, at similarly spaced intervals, and in a similar manner, as the A-portion of the side frame 13 with bearings 18 (see Figures 1, 2 and 4) of a construction substantially like the bearings 16 above described, and in the thus juxtaposed or paired bearings 16 and 18, throughout the section A, I rotatably mount rollers 19, illustratively twelve in number, as above noted, rollers 19 being of a construction better shown in Figure 4.

The rollers 19 are made preferably of any suitable solid dielectric material; they may, for example, be made of "bakelite" or even of a material like glass, and they are provided with stud shafts 19^a and 19^b receivable respectively in the 20 bearings 16 and 18 (Figure 4), being thereby mounted for free rotation. As is better shown in Figures 2 and 4, the rollers are closely spaced, and are parallel to each other, forming a supporting or conveying surface aligned with the 25 entry chute 11 (Figure 1) and when driven in counter-clockwise direction, as viewed in Figure 1, act to move the products or articles presented thereto from the chute 11, in a direction toward the left. The rollers 19 are driven in a manner 30 more clearly hereinafter described, it being sufficient at this point to note that, referring to Figures 4 and 2, the rollers 19 are provided at the ends thereof nearest the side frame member 13 with a belt-receiving groove 19^c.

The rollers 19 of section A are thus effective to bring the product or packages or articles to be sterilized to the section B which, as above noted, is in the treatment zone or zones and forms a part thereof, as will be more clearly presently 40 described, while the products, packages, or articles, having emerged from the treatment section B in their movement toward the left (Figures 1 and 2) are carried away from section B and discharged onto the discharge chute 12 (Figure 1) 45 by rollers 20 (Figure 2) which are illustratively twelve in number, as earlier noted, and which, moreover, are of a construction identical to that of rollers 19 above described in detail; at one end thereof they are rotatably supported in the bearings 16 of the C-portion of the side frame 13 and at their opposite ends they are supported in bearings 21, identical to the bearings 16 or 18 above described, supported in a front side frame or cantilever-like member 22 substantially like the member 17 above described and secured on the front side of the standard 15, being by the latter held in parallelism with the rear side beam 13. The rollers 20 of section C (Figure 2), like the rollers 19 of section A, are provided at the ends 60 thereof nearest the side beam 13 with belt-receiving grooves 20^c in order that they may be driven as later described in detail, in counter-clockwise direction, as viewed in Figure 1, and thereby effect movement of the product or packages toward the 65 left, to be discharged from the apparatus.

Since there are effective in the treatment zone of section B certain high potentials, all as later described, the shapes and dimensions of the side frame 13 and of the side frame members 17 and 70 22, will be seen to provide relatively very long paths from the intermediate or treatment zone section B to the otherwise grounded and metallic standards 14 and 15 (Figure 1), and thereby negative the loss of energy, as by leakage to ground, 75

from the treatment zone B, and it is particularly for a similar reason that the rollers 19 and 20 are preferably made of solid dielectric material.

In the treatment or intermediate section B of the construction, I provide roller-like members 23 (Figure 2) and they are constructed preferably as is better shown in Figure 3, being, as already earlier noted, illustratively sixteen in number, and being of greater axial length than the rollers 19 and 20 (see Figure 2). Members 23 (see now Figure 3) are made of solid dielectric material, preferably, however, of glass, "pyrex" glass, or quartz, by way of illustration, and particularly where made of glass, being, for reasons later described, made in the form of tubing, are relatively thick-walled, as is indicated in Figure 3. At their rear ends, as viewed in Figure 1, or at their left-hand ends, as viewed in Figure 3, the glass tube members 23 may be closed and provided with a stud-like extension 23^a supported in the bearings 16 above described and which extend throughout the B-portion (Figure 2) of the side frame or beam 13, and adjacent the bearing portion 23^a thereof, the glass tube members 23 are provided each with a belt-receiving groove 23^c, it being thus noted that all of the rotary members 19, 23 and 20 thus have their respective belt-receiving grooves 19^c, 23^c and 20^c all aligned (see Figure 2) adjacent to and lengthwise of the common side frame member 13. Moreover, it will be seen (Figure 2) that the rotary members 23 of section B are also closely spaced and that all of the rotary members are preferably of the same outside diameter; when members 23 are rotated in counter-clockwise direction, as viewed in Figure 1, they will be seen to form a continuation of the conveyor section A which includes the rollers 19, and thus the product, packages, or the like, to be treated, may be given a steady movement from one end of the apparatus to the other, such movement being continued within and throughout the treatment section B.

Onto the rotary members 23 in section B (Figures 1 and 2) there is to impinge, as later pointed out, a discharge preferably in the form of a corona-like discharge and, turning now to Figure 3, the wall or walls of the members 23 are to form the dielectrics or capacitances between the lower end of such discharge and a conductive means 24 within the tubular members 23. This conductive means may take any appropriate or suitable form and most conveniently is in the nature of a metallic coating or metallic sheet lining related to the inside surface of the tubular members 23, the latter being preferably relatively accurately made to have substantially uniform wall thickness. The right-hand ends of the tubular members 23 have mounted therein metallic shafts 25 (Figure 3), the latter being secured in place in any suitable manner, as by a cement 26, and being in electrical connection with the metallic coating 24, as indicated at 24^a in Figure 3. By way of the shafts 25, the right-hand ends (as viewed in Figure 3) of the rotary members 23 are rotatably supported and maintained in alinement with or in the same plane as the rollers 19 and 20 of sections A and C, the shafts 25 being rotatably supported in bearings 27 which conveniently and preferably are of the metallic oil-less type and acting therefore to continue the electrical circuits continued by the shafts 25 because of their connection to the linings 24 of their respective tubular members 23.

Considering now the support of the oil-less bearings 27 and still referring to Figure 3, the

bearings 27 are each secured to or supported by upright conductive means, preferably taking the form of sheet metal tubes 28, one for each rotary member 23 (see Figures 2 and 1) and all aligned and mounted in spaced relation and preferably parallel to the vertical front wall 10^d of the housing 10 (Figure 1).

As is better shown in Figure 3, each vertical tube electrode 28 is preferably cut away at one side thereof in order to receive therein the bearing 27 which is secured in place in any suitable manner, as by screws, or the like, each bearing 27 being thus in good electrical contact or connection with its respective electrode tube 28. Preferably, also, the upper and lower ends of the vertical tube electrodes 28 are rounded over, as by plugs 28^a and 28^b (Figure 3) thereby avoiding sharp corners or points, the plugs thereby serving also as convenient means, being recessed, to receive respectively the studs 29^a and 30^a of insulating plate- or beam-like members 29 and 30, respectively, the latter being made of any suitable solid dielectric material, such as laminated "bakelite."

Members 29 and 30 are preferably of identical shape, the one (member 29) projecting upwardly from the bottom or base 10^c of the housing to which it is secured, as at 31—32, and the other being inverted and projecting downwardly from an upper portion of the housing 10 to which it is secured as at 33—34, and hence at two widely spaced points. In Figure 1 the juxtaposed relation of the dielectric supports 29—30 is clearly shown, and it will be seen that each is shaped, somewhat in the form of a horizontally elongated X, thereby providing a relatively long path from any one of the vertical electrode tubes 28 to any one of the points 31, 32 or 33, 34 of connection of the members 29 and 30, respectively, to the grounded housing 10. As will later be pointed out, the electrode tubes 28 are maintained at a relatively high potential and by this construction of the solid dielectric supports any tendency of loss of energy by leakage along the supports to ground is dependably negated. Also, the rounded configuration of the members 28 avoids undesired brush discharge or similar loss of energy.

Each member 28 (see Figures 2 and 3) being thus insulated from the vertical wall 10^d of the grounded housing 10 and spaced therefrom forms, as will later be pointed out, an air condenser whose characteristics and action take part in achieving certain of the unique features of the electrical sterilizing action.

Considering now the drive of the roller members 19, 23 and 20 of the sections A, B and C (Figures 1 and 2), I drive them synchronously or at the same surface speed and to insure this action, particularly where the diameters of the belt-receiving grooves thereof are properly proportioned to the diameters of the respective roller members (in the illustrative embodiment all of these diameters are preferably equal), I cause a single endless belt 42 to be effective upon and in all of these belt grooves or belt pulleys and achieve that arrangement preferably in the following way:

Extending underneath the roller sections A, B and C, and closely positioned to the bottom 10^c (Figure 1) of the housing 10, is a shaft 36 mounted in bearings 37 and 38 at the respective right and left-hand ends of the bottom or base 10^c. Bearings 37 and 38 are mounted for vertical adjustment on elevating screws 39 and 40, respec-

tively, and thereby the vertical spacing in a downward direction of the shaft 36 from the rollers of the conveyor means may be determined at will, for a purpose later described. Moreover, the shaft 36, being metallic, is preferably mounted close to the bottom 10^c of the housing 10 and also considerably to the rear (as viewed in Figure 1) of the vertical condenser electrodes 28, and thus is well spaced from high potential parts.

10 Spaced along the shaft 36 is a series of sheaves 41, one for each successive two or pair of the roller members of the conveyor means A, B, C, the sheaves 41 being grooved, like the roller members, to receive a round belt and being positioned, 15 as is better shown in Figure 1, so that the planes of the belt grooves therein fall between such successive pairs of roller members.

A single belt 42, preferably a round leather belt (or any other suitable and preferably non-conductive material) coacts with the driving sheaves 41 and the rollers to drive all of the latter; it extends from the endmost idler 51 (at the right-hand end of side frame 13) upwardly into and over the belt grooves 19^c of the endmost two 25 rollers 19 of section A, thence downwardly to the endmost sheave 41 on shaft 36 about which it passes to continue upwardly over and into the belt grooves 19^c of the next two rollers 19, thence downwardly to the next sheave 41 on the shaft 30 36, and so on with respect to each successive pair of rollers in all three groups A, B and C and related or allocated sheaves 41 on the shaft 36, the 90° turn in the belt for each sheave 41 and pair of roller members being as is better shown in 35 Figure 3. The belt 42 finally comes over the belt grooves 20^c of the last pair of rollers 20 of the group C (see now Figure 1), whence it extends downwardly over the left-end driving sheave 41, on shaft 36, from which it extends 40 upwardly (see left-hand portion of Figure 1) about an idler 50 mounted on the insulating side frame 13, and from idler 50 it extends horizontally throughout and underneath the entire 45 extent of the rollers 20, 23 and 19 to idler 51 at the extreme right-hand end of the insulating side frame 13, whence it goes upwardly to the first pair of rollers 19, as already above described, the belt being endless.

The shaft 36 is driven by an electric motor 52 or other suitable source of driving energy (Figures 1 and 2) preferably positioned at the side of the endmost rollers of the section C and secured to the bottom 10^c of the housing 10. Any suitable driving connection, such as a chain and sprocket drive 44, extends between the motor 55 and the drive shaft 36.

The rollers of conveying means A, B, C are driven to give the products a suitable rate of movement, preferably a rate that matches or 60 suits the rate of discharge of the products, where the latter are packaged, from a packaging machine stationed at the right of the apparatus.

The motor 52, upon being energized, therefore 65 effects a movement of the belt 42 throughout the circuitous path above described, and the belt being in engagement with the belt groove of each roller or rotary member of the conveyor means A, B, C drives them at uniform surface speed, all in counter-clockwise direction, as viewed in Figure 1.

The belt 42, being of non-conductive material, and the vertical spacing between the roller members and the shaft 36 with its pulleys 41 being substantial, there are thus interposed between 70 these parts and particularly between the roller

members 23 in the treatment zone or section B and the shaft and its pulleys sufficiently long belt lengths to minimize or negative loss of energy by possible leakage currents along the belt portions to the grounded shaft 36. Appropriate 10 tension of the belt to compensate for belt stretch that might accompany long-continued operation may be achieved by adjusting the shaft bearings 37 and 38 in downward direction by the adjusting screws 39 and 40, respectively, and it will be noted 15 that, though the belt 42 is of substantial length and the aggregate stretch or increase in length may be substantial, only a small adjustment of bearings 37 and 38, because of the numerous loops of the belt that extend downwardly to the numerous pulleys on the shaft, need be made to take up what otherwise might appear to be a substantial belt elongation.

Reverting now to the treatment zone and certain parts coating with the above described dielectric or glass tubes 23 of section B, it is first of all to be noted, referring now to Figure 2, that the products to be treated, illustratively packaged products, move in a straight line from the right-hand end of the conveyor means A, B, C right on through to the left-hand end, the path of movement being substantially along a straight line and hence only those portions of the electrically coacting tubular members 23 of the intermediate section B that are in line with the rollers 19 and 20 of sections A and C are effective in the product-conveying action and it is, therefore, with respect to such portions of the rotary tubular members 23, that the above-mentioned electric discharge is to be concentrated or made effective; accordingly, I mount above these portions of the members 23 a high voltage electrode arrangement which, in so far as certain other features of my invention are concerned, preferably takes the form or forms hereinafter described in detail, it being noted that whatever form or forms the high voltage electrode structure assumes, the extension or elongation of the members 23 forwardly of the apparatus insures also the positioning of the vertical condenser electrodes 28 sufficiently remote as to provide adequate space 30 for the mounting and supporting of the high voltage electrode arrangement.

In the space thus provided, and preferably directly over the above-mentioned effective covering portions of the members 23, I position a suitable insulating structure generally indicated at 60 (Figure 1) and it may and preferably does include a lower ring member 61 from which a suitable number of struts extend upwardly, preferably diagonally or inclined as it were to join an upper ring member 62 supported by the frame or housing 10 in any suitable manner for adjustment in an up and down direction, as is indicated by the metallic bracket 63 (Figure 1) connected to the upper insulating ring portion 62 in connection with a manually operable elevating screw 64, the construction of the insulating structure 60 and its mounting conveniently and preferably taking the form of that described in detail in my above-mentioned application.

The lower ring member 61 of the insulating support 60 thus insulatingly supports a suitable number, illustratively eight rotating electrodes, 71, 72, 73, 74, 75, 76, 77 and 78, each electrode being toroidal in shape; i. e., having a surface similar to that generated by revolution of a curve about an axis outside itself and with its convex side outward, and all of them being preferably aligned so that their axes of rotation, parallel to

the plane of the conveyor means A, B, C, and hence parallel to the path of travel of the packages or products D carried thereby, are coincident but extend along a line E—E (Figure 2) that is at an angle or diagonal to the otherwise straight line of travel of the product or packages D.

The electrodes 71, 72, etc. (Figures 1 and 2) are preferably of identical shape and dimension and hence the lowermost points therein fall in a straight line, the spacing of which from the conveyor means, or more specifically from the coacting capacity-forming tubular members 23, may be varied or predetermined by raising or lowering the insulating structure 60 as by the elevating screws 64. All of these electrodes are maintained at a high potential, a potential on the order of 150,000 volts and preferably an alternating potential of relatively high frequency, such as a frequency on the order of 640 cycles per second. Each succeeding electrode of the group rotates about its horizontal axis in a direction opposite from the direction of rotation of the next preceding electrode. Accordingly, electrodes 71, 73, 75 and 77 rotate all in one direction and electrodes 72, 74, 76 and 78 all rotate in the opposite direction, as indicated by the arrows in Figure 1.

A suitable high potential, illustratively as above-mentioned, may be applied to these electrodes in any suitable manner; preferably I employ a means and arrangement like that described in my above-mentioned application, to which reference may be had for certain details. That preferred arrangement includes a transformer casing 70 carried by the upper part of the housing 10 (Figure 1) and containing a high frequency transformer 80—81, whose low voltage winding 80 may be supplied with suitable high frequency energy, preferably at low voltage, from any suitable source such as an alternator 82, and whose high voltage winding 81 (the ratio of transformation being suitable to cause the winding 81 to produce a voltage on the order of 150,000 volts) having its one terminal grounded as at 83, and hence grounded to the housing 10, and hence connected to the front wall 10^d which, it will be recalled, forms with the vertical condenser electrodes 28 an air condenser earlier above mentioned; the other terminal of the high voltage winding 81 is carried by conductor 84 out of the casing 70 through a high voltage terminal construction 85 depending from the casing 70 and positioned substantially coaxially with and within the ring-like or cylindrical insulating structure 60 above described, whence the high potential of the winding 81 is communicated to the electrodes 71, 72, 73, etc., the insulating structure 60 thus dependably insulating these high voltage electrodes from the grounded housing and other parts of the apparatus.

With the high voltage circuit thus completed, bearing in mind the conductive coupling or relation of the interior lining or coating 24 in the glass tubes 23 (Figure 3) with their respective condenser elements or tubes 28, as earlier above described, there takes place a localized rupture of the air spaces or regions immediately underneath each rotating electrode toroid 71, 72, 73, etc., and extending downwardly to and terminating in the outer surfaces of the two rotary dielectric members 23 immediately underneath each rotating electrode. Thus, referring to Figure 2, where, as earlier noted, I provide sixteen glass tube members 23, it will be noted that I have

provided eight diagonally arranged rotating electrodes 71, 72 . . . 78, one for each pair of tube members 23 and that, moreover, the lowest point in each rotating electrode falls in a vertical plane that passes through the pair of rotary tubes 23 5 immediately underneath it and to which it is thus virtually allocated for immediate coaction electrically.

This local rupture, because of certain other features of arrangement and action, is preferably 10 in the form of a finely divided corona discharge, being thus made up of a multitude of individually minute or fine corona streamers for purposes later described, disruptive discharge or spark-over being prevented by reason of the action of 15 other capacitances in the circuit of each rotating electrode. More particularly, it will be seen that, where each rotating electrode coacts with illustratively two tubular members 23 immediately underneath it, the metallic linings or coatings 24 20 of the latter extend the high voltage circuit, forming capacitances with the corona discharge that impinges upon the outer surfaces of the two tubes 23 (the dielectric of the latter forming the intervening dielectric), whence the high voltage 25 circuit of that particular rotating electrode is extended by the air condenser formed by the two vertical tubular condenser elements 28 to which the coatings 24 of the two rotating members 23 are conductively connected. Those particular 30 two condenser electrodes 28 form with the front wall 10^d of the housing (the housing completing the return circuit to the other or grounded terminal of the high voltage winding 81 of Figure 1) an air condenser which is of itself sufficient to 35 withstand the maximum voltage of the transformer winding 81 without rupture or breakdown.

From each electrode member 71, 72, etc., therefore, the high voltage circuit is extended virtually in two parallel paths where each electrode co-acts with two rotary members 23 and their respectively related condenser elements 28.

From this relationship of parts, certain unique advantages follow. For example, the metallic coating or lining (or electrode) 24 within each 45 tube 23 is relatively narrow but elongated in dimensions when considered in the plan view of Figure 2, for example, and the flux emanating from the lower curved or spherical area of each rotating toroid shaped electrode 71, 72, etc., is 50 drawn toward and thus concentrated by the conductive coating 24, the encompassing and rotating glass or other dielectric of the rotating tube member 23, being uniform, insuring uniformity of concentrating action and permitting some but 55 not a detrimental amount of spreading of the emanating flux and hence of the corona-like mass of streamers. Where the radii of curvature of the rotating electrodes 71, 72, etc. are relatively 60 large, as in the illustrative embodiment above described, and in order to cause a greater area around or at the under or lowermost side or portion of each electrode to be effective as a corona-discharge-emanating means, particularly in the direction of the axis of rotation of the rotating 65 electrodes, I preferably cause, as already noted, each electrode to coact with more than one and illustratively two rotating tubular members 23, and hence with more than one and illustratively two conductive coatings or members 24. Accordingly, the extension of the member or members 24 in the direction transverse to the axis of its associated rotating electrode causes an increase in the length of the corona-emanating area of the electrode in the direction of the cir- 75

cumference thereof while relating a conductive member 24, insulated by the dielectric of the member 23, to each side, as it were, of the substantially median or central vertical plane (as viewed in Figures 1 and 2) through the electrode, achieves an increase in the other dimension (in the direction of the axis of rotation of the electrode) of the corona-emanating area thereof.

Thus, with relatively large radii of curvature of each electrode member 71, 72, etc., I am enabled to cause, due to such coactions as have just been mentioned, the production and maintenance of a mass of corona discharge or streamers which, in horizontal cross-section, is of relatively large area or dimension.

It is accordingly eight such masses of corona discharge that the arrangement of the eight rotating electrodes 71, 72, etc. with their coacting parts achieves and in order to give the apparatus a capacity for handling products or packages whose width or dimension in the direction of the axis of the conveyor rollers 19 and 20 is relatively large compared to the axial lengths of these rollers themselves, these electrodes are arranged along the diagonal E—E of Figure 2, as above described, so that any package or product, moving along the conveyor means A, B, C from the right to the left (Figures 1 and 2) no matter what its width within the range of the lengths of the conveyor rollers, is caused to have each portion or segment in the direction of its length or path of travel subjected to the ionizing action and corona-like discharge before it emerges from the treatment zone or section B.

For example, while the discharge action of electrode 78, may, because of the dimensions or the package or article, be of insufficient dimension transversely of the path of travel to effect complete sterilization, such portions thereof as are not sterilized by electrode 78 are nevertheless effectively treated and sterilized by the action of one or more or all of the succeeding electrodes, as the package or product continues to move toward the left.

In this connection, the individual condensers above described in the circuit of each rotating electrode 71, 72, etc. achieve certain other advantageous actions. For example, and considered broadly, it will be seen that the energy output of the high voltage source 81 of energy is subdivided into a multitude of parallel circuits, illustratively and ultimately sixteen in number, one for each member 23 and its related condenser electrode 28. Should an article or a portion thereof or a portion or the whole of the contents of a package of material be, for some reason, in such a condition as, for example, wet, so as to give the package or material an unusual or unexpected permittivity, making that portion or part of the product of unusually high conductivity, the individual parallel circuits and the individual capacities therein included, for example, the condenser between the electrode discharge and the metallic coating 24 (with the dielectric of member 23 as its dielectric) and the capacity formed by an individual condenser tube electrode 28 and the front wall 10^d of the housing, are self-protective and, moreover, the latter-mentioned condenser acts at once to limit the current flow in its particular circuit to a safe or maximum permissible limit, thereby preventing the dissipation in that particular circuit of all of the high voltage energy and preventing therefore the shunting away from the remaining parallel circuits in which sterilization is being carried on, of

the high voltage energy necessary to continue such sterilization.

These various parallel circuits, therefore, are mutually interacting and mutually self-protecting and insure continuity of sterilizing action in spite of what might otherwise be circumstances fatal to sterilization of products or materials already in the treatment zone.

Accompanying the above described action is the coaction of the oppositely rotating electrodes 10 upon packaged products, and by this coaction there is overcome and dependably negated any tendency or action that deflects or refracts the discharge away from the vertical end or side walls of the package itself, as the package moves into or through the mass of corona discharge that is individual to each electrode and which streams downwardly from the above described relatively large surface area of the lower portion, as viewed in Figure 1, of each rotating toroid electrode, and in this connection reference is now made to Figures 7 and 8. In Figure 7 a package D is shown, as viewed from the right-hand end of Figure 2, in relation to an electrode, for example, electrode 71, that rotates in clockwise direction when viewed from that end of the apparatus, and in Figure 8 is shown the same package D in relation to the next succeeding electrode, for example 76, whose direction of rotation is reversed.

In Figure 7, also, there is indicated, as by the stippling 77^a, so much of the effective discharge-emanating area of electrode 71 as would be visible or apparent when the electrode is viewed as seen in Figure 7, and with the electrode moving in clockwise direction, it has a tendency to sweep, as it were, the individual discharge or corona streamers (which extend in a general vertical direction, as viewed in Figure 7) in a direction from the right toward the left. The discharge, however, tends to persist along the outside surface of the right-hand wall of package D and also throughout the interior of the package and hence throughout its contents, excepting possibly for a portion of the contents immediately adjacent the right-hand wall of package D, due to flux refraction, the above mentioned persistence or tendency of the flux or discharge to follow the vertical side wall, or other factors.

But when the package D comes into the discharge zone under the next electrode 76 (Figure 8) oppositely rotating, the rotation of the latter tends to sweep the flux, emanating from the area 76^a thereof, in a direction toward the right, and hence toward and beyond the right-hand vertical wall of package D. With the discharge streamers moving in that direction, however, the portion of the contents to the left of the right-hand wall of package D (Figure 8), and which might have escaped sterilization under electrode 71 of Figure 7, is now thoroughly sterilized. Due to the inclination of the axis E, E (Figure 2) of rotation of the toroidal electrodes, this sweeping action or movement of the streamers of the discharge is in a direction also at an angle to the vertical front and end walls of the package, and due to the opposite directions of movement of sweeping of the discharge relative thereto, as will now be clear from what has been above said in connection with Figures 7 and 8, the portions of the product within the package and immediately adjacent the front and rear vertical end walls of the package cannot, in a similar way, escape sterilization, and thus uniform sterilization throughout the entire contents of the package is dependably achieved. Moreover, with numerous

electrodes 71, 72, 73, etc., for example the eight illustratively above described, there is achieved a repeated reversal of sweeping movement of the discharge or corona streamers with respect to the vertical walls of the package, and thus certainty of complete sterilization is assured.

The regions of flux concentration or the masses of corona streamers respectively individual to the various electrodes are, furthermore, as is now clear, of sufficient dimension in a direction transversely of the conveyor means A, B, C (Figure 2) that, when viewed along the length of the conveyor means, they overlap and form a barrier as it were, of dielectric stress or of corona discharge that extends entirely across the conveyor means, due to the diagonal relation of the axis E, E of Figure 2, and thus the passage of any product or article within the dimensions of the conveyor means and along the latter is effective to cause every portion thereof to move through this barrier and thus to be sterilized.

The action of destruction of the insect life follows with great certainty; the product, illustratively flour, corn-meal, cereals, or the like, has a higher average permittivity than the air intervening the particles of the material itself and of the air which the material itself displaces in the treatment zone or regions, causing a redistribution of voltages in the high voltage circuit. As a result, dependable ionization throughout the material and particularly within the packages where it is packaged, takes place as does also corona discharge, the latter occurring at a lower point on the voltage wave with a consequent increase in its duration. Because the contaminating life has substantially infinite permittivity, being in effect electrically conducting, the insects, larvae, pupae, eggs, etc., thereof, are sought out by the corona streamers, the latter pass therethrough, and bring about their destruction.

Puncturing of the pasteboard or other non-conductive material of the package, where the material is packaged, is dependably guarded against. The material of the packages or cartons acts as a condenser dielectric or dielectrics which becomes serially related to the dielectrics of other capacitances in the high voltage circuit or circuits, such as the glass wall of the member or members 23 (Figure 3), or the air dielectric of the condenser 28—10^d (Figures 2 and 3), and the latter capacities are proportioned so that the resultant redistribution of voltages throughout these serially related condenser dielectrics is such that the voltage gradient across the material of the carton is below the puncturing gradient and hence puncturing of the walls of the carton is positively precluded. Also the preferred mode of operation wherein spark-over or disruptive discharge in the treatment zone or regions, as distinguished from the streamer or corona-like discharge above described, is prevented, coacts to guard against damaging the material of the carton or package.

The large-surfaced toroidal form of electrodes 71, 72, 73, etc. achieves other advantages besides those above-mentioned. For example, pitting of the external surface is negated due to the large and continually renewed surface portions thereof that are made effective, during the rotation, for the emanation of corona discharge; stated differently, heating or other physical change is minimized because I am enabled to avoid steady or constant emanation of discharge from a point or points and instead spread the discharge as it

emanates over a relatively large area (see portions 77^a or 76^a of Figures 7 and 8, for example), the surface or surfaces of which, however, are constantly being replaced or renewed due to the rotation of the toroidal electrode. The speed of rotation is preferably relatively high, say on the order of 4000 R. P. M., thus making any portion of the area or surface of the electrode that is presented toward the parts 23 for corona emanation effective only for an infinitesimally small interval of time.

By raising or lowering the insulating structure 60, I may vary the character of discharge action in the treatment regions or zones and I may also accommodate the apparatus to different vertical dimensions of products or packages, or the like. The toroidal electrodes, per se, are replaceable as hereinafter described, and I may in that manner vary their effective diameter as well as other radii of curvature, and thus vary accordingly the character, nature and other characteristics of the action in the treatment zone to suit practical conditions as may arise.

Considering now in detail the construction, mounting and driving of the toroidal electrodes, it is first to be noted as appears from Figure 1, that the toroidal electrodes are paired to form as it were as many units structurally as there are successive pairs of electrodes; thus electrodes 71—72 are paired to form a single unit, the next two electrodes 73—74 are paired to form another unit, and so on, thus simplifying the mounting and supporting of all of the electrodes from the solid dielectric supporting structure 60. Since these pairs or units of electrodes and their drives and mountings are substantially identical, it will suffice to describe in detail one pair or unit, illustratively that unit which includes the electrodes 71—72 of Figure 1, and accordingly reference may now be made to Figures 5 and 6 of the drawings in which the structure of that unit is shown on an enlarged scale and in detail.

As is better shown in Figure 5, the double electrode unit comprises two structures 91 and 92 which in turn are substantially identical, including respectively supporting arms 93 and 94 which, when placed back to back, as shown in Figure 5, and secured together, form the double electrode and driving structure or unit. Accordingly, it will suffice to describe in detail one of the structures 91—92 and hence consideration may now be given to the structure 91 which is shown in cross-section in Figure 5 and in side elevation in Figure 6, as seen along the line 6—6 of Figure 5.

The arm 93 (Figures 5 and 6) is concaved or hollow as at 95, and its lower end is disk-like in shape (see Figure 6) as at 93^a, being bored out as at 93^b (Figure 5) to receive therein a sleeve member 96, hereinafter called the "stator sleeve". Stator sleeve 96 has built onto it or supports the stationary element of an electric motor, preferably an alternating current motor of the induction type, and hence that stationary member is illustratively termed the stator. The stator comprises a stator core 97 built up of laminations which are centrally apertured to fit onto stator sleeve 96, abutting at the left against a shoulder formed by a stepped and larger-dia metered extension 96^a of the stator sleeve 96 between which and a threaded collar or nut 98, threaded onto a threaded intermediate portion of the stator sleeve 96, the stator core 97 is securely clamped. The nut or collar 98 is rigidly secured to the portion 93^a of the arm 93 by screws 99 (Figures 5 and 6) which thus hold the stator sleeve 96 well seated.

in the bore 93^b (Figure 5). The stator core 97 may also be provided with annular guards 100—101 of suitable sheet material, L-shaped or flanged in cross-section, and one on each side of 5 the core 97, secured in place by rivets 102 which thus also aid in clamping the laminations of the core 97 together. The latter, moreover, is peripherally slotted to receive suitable coils to form a winding 103, one terminal of which is grounded 10 to the core 97 as at 104, and the other terminal of which is carried by conductor 105 through a suitable aperture in the sheet metal guard 101 and through a suitable channel or hole 93^c in the disk portion 93^a, thus communicating with the 15 hollow or concave portion 95 of the arm 93, whence the conductor is extended further as later hereinafter described.

The winding 103 may be of a character disclosed in my co-pending application filed of even 20 date herewith, Serial No. 747,436, and the core 97 may also be provided with peripherally positioned shading coils, as disclosed in the said application but not shown in the drawings herein. The induction motor of which this stator core 25 structure forms a part is thus given self-starting characteristics.

The motor core that coacts with the stator core 97 is indicated at 106 and it is made up of 30 annular laminations whose inside diameter is slightly greater than the outside diameter of the stator core 97, thus providing adequate air gap and mechanical clearance, and it is provided with a squirrel cage type of winding, as is indicated by the annular members 107—108 and the cross-conductors, in the form of rivets, shown at 109.

This annular rotor core 106 is supported for 35 rotation concentrically with the above-described stationary stator 97—103 by a rotor housing generally indicated at 110 and comprising a disk-like vertical end wall 110^a and a cylindrical or drum-like wall 110^b which carries an inwardly directed flange 110^c against which the rotor core 106 is seated, the cylindrical portion 110^b being bored out snugly to receive the annular rotor core 106. 40 A complementary member 111 has a vertically extending annular end wall 111^a with a cylindrical portion 111^b shaped at its left-hand periphery to telescope into the cylindrical portion 110^b of the rotor support 110, and the complementary member 111 is secured to the rotor support 110 by screws 112 which, when driven home, cause the portion 111^b to securely clamp the rotor core 106 between it and the radially extending flange 110^c.

45 The rotor housing or support 110 has its disk-like end wall 110^a interiorly counterbored as at 110^d to snugly receive therein the disk-like head or end flange 113^a of a shaft 113 which extends into and coaxially with the stationary stator sleeve 96, member 110 being secured to the end flange 113^a as by a suitable number of screws 114.

50 Shaft 113 is in turn rotatably supported by and within the stator sleeve 96, whereby rotor core 106, now encased by the parts 111 and 110, 55 may freely rotate with these parts, about the axis of the rotor sleeve 96, the right-hand end of annular member 111 being apertured and recessed about the periphery of its axis to receive felt or similar washers 114 which bear against, 60 and thus form a dust-proof seal with, the cylindrical face of the hub-like extension (toward the left, as viewed in Figure 5) within which the counterbore 93^b is formed. Thus all the working 65 parts of the motor are totally enclosed and

sealed, including also the parts presently to be described.

The shaft 113 is rotatably supported in the stator sleeve 96, preferably by suitable anti-friction bearings, illustratively ball bearings 115 and 116. The outer race 115^a of the bearing 115 is received within and held by the stepped or larger-diaetered portion 96^a of the sleeve 96, a spacer ring or washer 140 being interposed between it and the head 113^a of the shaft 113, while 10 the inner race 115^b rests at its left-hand end against a shoulder of the stepped shaft 113; its right-hand end is abutted by a sleeve 117 which extends toward the right, being stepped or reduced in diameter, as is also the extreme right-hand end portion 113^b of the shaft 113. Upon 15 the latter is received the inner race 116^a of the anti-friction bearing 116 and it abuts against the right-hand end portion of the sleeve 117. The reduced end portion 113^b of the shaft 113 is 20 threaded to receive a nut 118 which bears against the inner race 116^a and clamps the latter and the sleeve 117 and the inner race 115^b against the left-hand shoulder of the shaft 113, thereby rigidly fixing these parts to rotate with the shaft 25 113. The outer race 116^b of the bearing 116 is seated, fitted or secured within the right-hand end of the stator sleeve 96, preferably abutting against a shoulder formed in the latter, as shown in Figure 5.

30 Accordingly, the stator 106 with its housing parts 110—111 is thus supported for free rotation relative to the stator 97 and its stationary supporting sleeve 96, and to rotate also relative to the latter, the entire assemblage of these parts 35 being, as will now be clear, capable of assembly relative to the supporting arm 93 and detachably so, by screws 99 and the related interfitting parts.

The complementary housing member 111 is 40 provided with a radially extending peripheral flange 111^c, preferably integrally formed therewith, while the housing or rotor support 110 is counterbored as at 110^e to form a seat for a ring-member 120 which is provided with a peripherally or radially extending flange 120^c forming a juxtaposed part to the above-mentioned radial flange 111^c, but being detachable by reason of the detachable securing of the ring-member 120 to the member 110 by the screws 121. 45

50 When ring-member 120 is detached, the toroidal electrode 71 may be slipped, in an axial direction, onto or over the housing portions 110^b and 111^b to bring its right-hand portion in abutting relation to the flange 111^c, whereupon the 55 ring-member 120 is replaced, bringing the juxtaposed flange 120^c into engagement with the left-hand part of the toroidal electrode 71, the outside diameters of the parts to the inside of these flanges being such as to closely match the inside 60 diameters of these side portions of the electrode 71, the latter being thus securely but detachably mounted onto the rotating rotor housing 110—111 and coaxially therewith.

The toroidal electrode 71 is preferably made 65 hollow and hence preferably made of sheet-like metal, preferably nickel or a nickel alloy, and may be formed in any suitable way as by spinning, casting and machining, by electro-deposition, or the like. Referring to Figures 5, 1 and 2, the external surface of the electrode 71, generally toroidal in shape, is of large radius of curvature 70 (as seen in cross-section, as in Figure 5), the large radii of curvature being accentuated by distribution peripherally about a large diameter 75

through the axis of rotation of the electrode itself.

Where made in hollow form or shape, the electrode 71 may be made to coact, due to its resultant inherent springiness, in a yielding gripping there-
of between the securing parts 111^c and 120^c.

As illustrative of the radii of curvature or dimensions of the electrodes 71, 72, etc., and referring to the electrode 71 of Figure 5, it may be noted that the maximum diameter of the electrode 71 may be on the order of 11" and the radius of curvature in cross-section or in a plane through the axis of rotation, may be on the order of 2".

The upper ends of arms 93 and 94 (Figures 5 and 6) have respectively integrally formed therewith cross-arms 122^a and 122^b, parts 122^a and 93, and parts 122^b and 94 being virtually L-shaped. The ends of cross-members 122^a and 122^b are provided with split bushings 123 and 124, respectively, the axes of which, however, extend parallel to the axis of rotation of the electrodes 71 and 72, respectively, the split bushings being given a clamping action by reason of the clamping screws 125 related thereto. The arms 122^a and 122^b and the bushings 123 and 124 are interiorly channelled or hollowed out as at 126 forming channels through which the conductor 105 may be led.

The arm 94 of the structure 92 (Figure 5) is thus the same as the arm 93, being an exact duplicate thereof and having therein a conductor 127 (Figure 5) leading to the motor which drives the electrode 72. L-shaped arm 94—122^b with its electrode 72 and the encased driving motor therefor, is laid against or face to face with the L-shaped arm 93—122^a, and the two are secured together as by screws 128 at the upper end thereof and as by a bolt 129 (Figure 5) fitted into registering slots 130 (Figure 6) in the lower ends 10 of the two arms, thereby providing the double electrode unit structure 71—72, by way of illustration. The latter will thus be seen to have a T-shaped support, the cross-member or arm 122 of which is formed by the oppositely extending parts 122^a and 122^b.

In thus assembling the parts of a single double electrode unit, and with the motors thereof uniformly constructed as to direction of rotation, the backing of one motor against the other, as it were, causes one electrode or motor to rotate in one direction and the other motor and electrode to rotate in opposite direction about the now aligned coincident axes or common axis thereof.

Thus, the four pairs of oppositely rotating electrodes earlier above-mentioned are each provided with a cross-member 122 with the split bushings 123—124; the latter are assembled to two metallic and preferably tubular supports 131—132 (Figures 6 and 1), the tubular support 131 (Figure 6) being apertured at intervals corresponding to the spacings of the cross-members 122 or bushings 123 therealong, so that the conductors 105 and 127 of the motors of each pair may be brought into the tubular support 131, for a purpose later described.

The tubular supports 131—132 are parallel to each other and lie in a plane parallel to the plane of the conveyor means in section B (Figures 1 and 2) and are held fixedly in the lower ring-portion 61 of the solid dielectric support or frame 60 above described, being equidistantly positioned on opposite sides of a diameter of the latter, a diameter that is coincident with or lies in the vertical plane through the diagonal line E—E of Figure 2. Supports 131 and 132 are rigidly se-

cured to the ring-portion 61 by clamping members 133 and 134 (Figure 1) which extend peripherally of the ring-member 61 to an appropriate extent and overlap the upper edge thereof, thereby to avoid undue concentration of the weight of 5 the illustratively four pairs of electrode and driving structures.

The split bushings 123—124 securely clamp the various cross-members 122 to the spaced tubular supports 131 and 132, the arrangement, moreover, being such that the spacing of the paired electrodes or units along the tubular supports may be varied when desired; and the same clamping action also insures a good electrical contact between the tubular supports and the T-shaped 15 arm or frames 93—94—122 (Figures 5 and 6) of the double electrode structure so that, when the high voltage side of the transformer winding 81 (Figure 1) is extended by conductor 84 through the insulating bushing or terminal construction 20 85 and by a conductor 135 to one or both of the tubular supports 131—132; the latter as well as the electrode units or structures supported thereby are placed and maintained at the high potential of this transformer, the electrodes 71, 72, 73 25 26 coacting with the other parts as already above described in detail.

Referring back to Figure 5, in order to avoid any detrimental action upon the anti-friction bearings by the passage of any current there-through from the stationary motor parts to the rotating motor parts, I provide a recess 113^e in the left-hand face of the shaft head 113^a, the recess being outwardly or radially exposed to the inner face of the left-hand end of the stator sleeve 96. In this recess I mount a brush 141 extending radially and contacting with the inner cylindrical face of the portion 96^a of the stationary stator sleeve 96. The brush 141 may be of any suitable construction; for example, it may be in the form of a carbon, copper, sponge copper, or the like, suitably spring-pressed into contact with the inner face of the stationary sleeve 96. As the electrode 71 with its rotor housing and hence with the shaft 113 rotates, the brush 141 45 sweeps about the inner face of the portion 96^a of the stationary stator sleeve 96, and makes and maintains, continuously, a good electrical interconnection or contact between the stationary parts and the rotating parts of the motor. This 50 connection shunts the energy flowing in the high voltage circuit away from the balls or rollers of the anti-friction bearings and thus avoids any possible detrimental action on the latter.

The recess 113^e in the shaft head 113^a and 55 hence the brush therein contained is accessible for adjustment, replacement or repair, from the exterior, by way of a threaded aperture in the vertical wall portion 110^a of the rotor housing, the aperture being closed by a threaded plug 142. 60

Suitable means for lubricating the bearings 115 and 116 are also provided and they may take the form (see Figure 6) of a lubricating duct 143 extending radially through the portion 93^a of the arm 93 and communicating with the innermost 65 (right-hand, as seen in Figure 5) end portion of the counterbore 93^b, therein; through this lubricating duct 143 suitable lubricant may be forced or injected into this end portion of the counterbore 93^b and hence to the bearing 116, and 70 through the latter and by way of the spacing between the sleeves 96 and 117 (Figure 5) to the bearing 115. The duct 143 (Figure 6) is closed by a threaded plug 144.

As above pointed out, one terminal of the 75

motor windings 103 is grounded (see the ground at 104 in Figure 5) and this, being true as to all of the motors of the electrodes 71, 72, 73, etc. (Figures 1 and 2) the same side or terminal of all 5 of these windings is to be electrically connected, through the motor parts and arms 93-94 and cross-arms 122 to the metallic tubular supports 131 and 132 to which (see now Figure 1) the high voltage side of the transformer winding 81 is connected as above described, that one side or terminal of all of these windings being thereby electrically extended into the transformer casing 70 by way of conductor 135, high voltage terminal 85 and conductor 84 (Figure 1); conductor 84 is 10 also connected to one terminal of the secondary winding 145 of a low voltage, low frequency transformer whose primary winding 146 is connected, as diagrammatically indicated in Figure 1, to a suitable external source 147 of alternating current energy, such as the usual A. C. power supply circuits of 110 or 220 volts, 60-cycle current.

The secondary winding 145 is, because of its connection to the high tension conductor 84, at the high potential of the latter, but the transformer 146-145 is insulated for that high potential, as described in my above-mentioned co-pending application, and thus the primary winding 146 and its circuit to the source 147 is adequately protected from this high potential.

30 The other terminal of the secondary winding 145 is connected by conductor 148 to a separate conductive member 149 in the insulating bushing 85 (the detailed construction of which is shown in my above-mentioned application) and is insulated 35 from the high voltage conductor therein for a voltage on the order of 110 or 220 volts. Conductor 149 is connected to all of the conductors 105 and 121 (Figures 5 and 6) which are snaked through one of the tubular supports, for example support 131, and which lead to the other terminals of the windings 103 of the various motors. And thereby the circuits to the stator windings of these various motors are completed so as to supply 40 energy thereto and effect rotation of the toroidal electrodes 71, 72, 73, etc., in the manner and with the actions and results certain of which were illustratively described above in detail.

50 Considering further certain of these actions, reference might again be made to the high speed of movement or the high rate of peripheral velocity of the active surfaces of the toroidal electrodes; this velocity is, as above indicated, on the order of 10,000' per minute. Because of this high velocity, the desired character of discharge is 55 effectively maintained. For example, the active electrode surfaces are effectively cooled and such heat rise as would materially facilitate the disintegration of the electrode metal or the separation from the electrodes of metallic particles is 60 minimized and thereby tendencies toward the arc type of discharge negated.

Furthermore, the high velocity of electrode surface movement achieves also a movement, at 65 relatively high velocity, of the air in the discharge gap or in the treatment zone, and thereby the ionized air in the treatment zone is rapidly removed. There thus results substantially constant or uniform voltage of disruption.

The large cross-sectional area of the corona-like discharge emanating from each toroidal electrode results to a substantial degree from the high peripheral velocity of the electrode surface.

70 As earlier above noted, two roller members of the conveyor section B are allocated to each toroidal electrode, in the preferred embodiment of

my invention, but that illustrative arrangement is not to be interpreted in a limiting or restricting sense, for under some circumstances I may allocate to each toroidal electrode only one such roller member or more than two. To better understand certain aspects of the coaction of these parts it might first be noted that, whatever the allocation of a lower roller member or members to a toroidal electrode, I prefer to achieve, as nearly as is practicable, substantial equality between the maximum voltage gradient and the average voltage gradient across the treatment zone between the parts. Such substantial equality is electrically best or most simply achieved if there were juxtaposed or allocated to a toroidal 15 electrode only a single coaxing roller member providing that the radii of curvatures of the two coaxing parts approximate equality. But the radii of curvatures of these two coaxing parts are in turn dependent upon the thickness, in the 20 direction of the discharge, of the product or packaged products to be treated and hence are dependent upon the spacing therebetween; for example, the greater the thickness of the material or packaged material to be treated, the 25 greater would these radii be. For example, where the radius of curvature of a toroidal electrode, as viewed in Figure 5, is on the order of 2", the radius of curvature of a single roller member allocated to it should be about the same, and with 30 such a relation of the parts the maximum and average voltage gradients across the treatment zone or discharge region therebetween likewise approximate equality, where the maximum thickness of product or packaged product to be treated 35 is on the order of say 6". A preferred ratio of minimum radius of curvature to maximum thickness of material to be treated is 1 to 3.

However, where packaged products are to be treated, it is desirable that the package or carton 40 be at all times supported by at least two rollers. In practice, packages or cartons are met with whose dimensions are too small to be supported simultaneously by two rollers of a radius of curvature on the order of 2", and it is therefore impracticable to use rollers of such dimensions.

Accordingly, two or more roller members are allocated to each toroidal electrode and they are made of sufficiently small radius of curvature to meet the mechanical requirement of the package 50 or carton being supported simultaneously by at least two roller members, but they are at the same time proportioned with respect to the radius of curvature of the toroidal electrode to achieve across the discharge region of the latter 55 substantial equality of maximum and average voltage gradients.

Illustratively, therefore, where the radius of curvature of the toroidal electrode is 2" and where the minimum length of package in the direction of its travel along the conveyor means A, B, C, is 6", the two roller members allocated to each toroidal electrode, to meet the above mechanical and electrical conditions, have a radius of curvature on the order of 1 $\frac{1}{16}$ " and are 65 spaced center to center on the order of 2 $\frac{7}{8}$ ". This specific embodiment is therefore to be interpreted as illustrative.

The rotation of the rollers in the section B of the apparatus, these rollers being made of solid 70 dielectrical material, illustratively "pyrex" glass, or the like, and upon which the discharge impinges, is also highly advantageous in that the life of the roller members or the dielectric thereof is greatly increased. For example, any portion of 75

the discharge-receiving surface thereof is not continuously in discharge-receiving position but is periodically removed therefrom, and, moreover, during such removal is subjected to a desirable cooling effect or action. Deterioration or other detriment effects thereon is thus negated.

It will thus be seen that there has been provided in this invention an apparatus in which the various objects above noted, together with many thoroughly practical advantages are successfully achieved. It will also be seen that the apparatus is of a thoroughly practical character, is of dependable operation, and well adapted to meet various practical conditions of use.

As many possible embodiments may be made of the above invention and as many changes might be made in the embodiment above set forth, it is to be understood that all matter hereinbefore set forth or shown in the accompanying drawings, is to be interpreted as illustrative and not in a limiting sense.

I claim:

1. In electrical treating apparatus, in combination, means for moving a product to be treated along a given path, electrode means spaced from said path and comprising a plurality of rotatable toroidal electrode members, means supporting said electrode members offset one from another transversely of said path, means for effecting rotation of certain of said members in one direction and others in reversed direction, and means including a source of suitable potential connected to said electrode means for effecting discharge through the product moving along said path.

2. In electrical treating apparatus, in combination, means for moving a product to be treated along a given path, electrode means spaced from said path and comprising a plurality of rotatable toroidal electrode members, means supporting said electrode members offset one from another transversely of said path, means for effecting rotation of said electrode members, a source of high potential, and means including condenser means for completing the circuit of said source and said electrode means to maintain discharge in said path.

3. In electrical treating apparatus, in combination, means comprising a plurality of rollers of dielectric material for movably supporting a product to be treated along a given path, and an electric discharge circuit comprising electrode means above said rollers, a source of suitable potential, and conductive means within certain of said rollers and extending along the axis thereof for effecting discharge of products moving in said path.

4. In electrical treating apparatus, in combination, means comprising a plurality of rollers of dielectric material for movably supporting a product to be treated along a given path, and an electric discharge circuit comprising electrode means above said rollers, a source of suitable potential, said rollers being in the form of tube-like members, and conductive means within certain of said rollers for coaction with said source and said electrode means.

5. In electrical treating apparatus, in combination, means comprising a plurality of rollers of dielectric material for movably supporting a product to be treated along a given path, and an electric discharge circuit comprising electrode means above said rollers, a source of suitable potential, said rollers being hollow and made of a material like glass and having conductive

means on the inside surface thereof and included in said circuit.

6. In electrical treating apparatus, in combination, an electric discharge circuit comprising a source of suitable potential, electrode means, rollers of dielectric material spaced from the latter for movably supporting a product to be treated in the discharge region of said electrode means, conductive means below the dielectric material of said rollers and coacting therewith to form an electrode for concentrating the discharge at the lower end of said discharge region, and capacity-forming means, one terminal of which is connected to said conductive means.

7. In electrical treating apparatus, in combination, an electric discharge circuit comprising a source of suitable potential, electrode means, rollers of dielectric material spaced from the latter for movably supporting a product to be treated in the discharge region of said electrode means, conductive means below the dielectric material of said rollers and coacting therewith to form an electrode for concentrating the discharge at the lower end of said discharge region, said conductive means comprising a plurality of means each individual to a roller, and a plurality of condensers, each having a terminal thereof connected to one of said individual conductive means.

8. In electrical treating apparatus, in combination, an electric discharge circuit comprising a source of suitable potential, electrode means, rollers of dielectric material spaced from the latter for movably supporting a product to be treated in the discharge region of said electrode means, conductive means below the dielectric material of said rollers and coacting therewith to form an electrode for concentrating the discharge at the lower end of said discharge region, said conductive means comprising a plurality of conductive means each individual to a roller, a condenser electrode for each of said individual conductive means and electrically connected thereto, and a plate-like condenser electrode common to all of said individual condenser electrodes, for completing said circuit.

9. In electrical treating apparatus, in combination, an electric discharge circuit comprising a source of suitable potential, electrode means, rollers of dielectric material spaced from the latter for movably supporting a product to be treated in the discharge region of said electrode means, conductive means coaxial with and within each roller, and capacity-forming means completing said circuit from said conductive means to said source.

10. In electrical treating apparatus, in combination, an electric discharge circuit comprising a source of suitable potential, electrode means, rollers of dielectric material spaced from the latter for movably supporting a product to be treated in the discharge region of said electrode means, said rollers having conductive means therein, a combined condenser electrode and support for an end of each roller and in electrical connection with the conductive means in the latter, and a companion condenser electrode to form there-with a capacity.

11. In electrical treating apparatus, in combination, an electric discharge circuit comprising a source of suitable potential, movable electrode means having a surface smoothly curved and continuous along the path of movement, means spaced from said electrode means for transporting a product to be treated into the discharge

region of said electrode means, and means forming a condenser capable of withstanding the potential of said source without breakdown for causing local rupture in said discharge region.

5 12. A treating apparatus like that of claim 11 in which the transporting means includes a cylindrical product-carrying member of solid dielectric material which is included in said discharge circuit for receiving the discharge from 10 said electrode means.

13. A treating apparatus like that of claim 11 in which the transporting means is made of solid dielectric, such as glass, which is included in said discharge circuit and which moves with the 15 product.

14. A treating apparatus like that of claim 11 in which the transporting means comprises a plurality of rollers and the electrode means comprises a rotating toroidal electrode whose axis is 20 substantially in line with the direction of travel of the product.

15. A treating apparatus like that of claim 11 in which the electrode means comprises a rotating toroidal electrode whose plane of rotation is 25 inclined to the direction of travel of the product.

16. A treating apparatus like that of claim 11 in which the electrode means comprises a drum-like support rotating about a generally horizontal axis, and electrode means substantially ring-like 30 carried by said drum.

17. An apparatus like that of claim 16 in which the electrode means comprises a drum-like support rotating about a generally horizontal axis and in which the electrode means is substantially 35 ring-like and is detachably mounted on the drum.

18. An apparatus like that of claim 11 in which the electrode means comprises a drum-like rotatable support carrying an electrode, and in which the said electrode is toroidal and the drum is 40 provided with means for detachably holding the electrode.

19. A supporting structure having extending laterally therefrom a sleeve, a stator carried by 45 said sleeve, an annular rotor extending about said stator, a rotor support for said rotor and having means rotatably supporting it coaxially with said sleeve, and electrode means carried by said rotor support.

20. An electrode and driving structure like that 50 of claim 19 in which the rotor support is in the form of a housing completely enclosing the stator, rotor, and their respective supports.

21. An electrode and driving structure like that 55 of claim 19 in which the means that rotatably supports the rotor support is accommodated within said sleeve.

22. An electrode and driving structure like that 60 of claim 19 in which an electrically conductive connection between the supporting structure and the rotor support is maintained by brush means coacting between a rotatable and a non-rotatable part.

23. In electrical treating apparatus, in combination, an electric discharge circuit comprising 65 a source of suitable potential, spaced electrode means having curved effective surfaces of radii of curvatures proportioned to the spacing therebetween to achieve approximation of equality between maximum and average voltage gradients 70 therebetween, and means for positioning a product to be treated in the space between said electrode means, the surface of one of said electrode means being conductive and the surface of the other being non-conductive.

75 24. In electrical treating apparatus, in combi-

nation, an electric discharge circuit comprising a source of suitable potential, spaced electrode means having curved effective surfaces of radii of curvatures proportioned to the spacing therebetween to achieve approximation of equality 5 between maximum and average voltage gradients therebetween, means for positioning a product to be treated in the space between said electrode means, one of said electrode means being in the form substantially of a cylinder and having a 10 non-conductive surface.

25. In electrical treating apparatus, in combination, an electric discharge circuit comprising a source of suitable potential, spaced electrode means having curved effective surfaces of radii 15 of curvatures proportioned to the spacing therebetween to achieve approximation of equality between maximum and average voltage gradients therebetween, means for positioning a product 20 to be treated in the space between said electrode means, one of said electrode means having a non-conductive surface and the other being in the form of a toroid, and means for rotating the toroidal electrode means at high speed.

25 26. In electrical treating apparatus, in combination, an electric discharge circuit comprising a source of suitable potential, spaced electrode means having curved effective surfaces of radii of curvatures proportioned to the spacing therebetween to achieve approximation of equality between maximum and average voltage gradients 30 therebetween, means for positioning a product to be treated in the space between said electrode means, one of said electrode means having a non-conductive surface, and means for rotating the 35 effective surface of one of said electrode means.

27. In electrical treating apparatus, in combination, an electric discharge circuit comprising 40 a source of suitable potential, spaced electrode means having curved effective surfaces of radii of curvatures proportioned to the spacing therebetween to achieve approximation of equality between maximum and average voltage gradients 45 therebetween, one of said electrode means being in the form of a roller member and having a non-conductive surface, and means for rotating said roller member to cause it to carry a product to be treated into the space between said electrode means.

28. In electrical treating apparatus, in combination, an electric discharge circuit comprising a source of suitable potential, spaced electrode means between which electric discharge takes 55 place, means for supporting a product to be treated in the discharge region between said electrode means, one of said electrode means having a smooth surface substantially continuous along the path of movement and means for giving the smooth surface of said one electrode 60 means a high velocity of movement.

29. In electrical treating apparatus, in combination, an electric discharge circuit comprising a source of suitable potential, spaced electrode means between which electric discharge takes 65 place, means for supporting a product to be treated in the discharge region between said electrode means, one of said electrode means being rotatable and having an effective surface substantially free from protrusions with all points thereon in a given plane normal to the axis of rotation lying along a substantially unbroken circumference whose center is substantially coincident with the axis of rotation, and means for 70 75

rotating said rotatable electrode means at high peripheral velocity.

30. In electrical treating apparatus, in combination, means for moving a product to be treated along a given path, electrical means spaced from said path and comprising a plurality of rotatable electrode members, means supporting said electrode members for rotation about axes in planes parallel to the said path and with the electrode members extending generally transversely of said path, each electrode member having an effective discharge surface which is continuous along a circumference thereof lying in a plane at right angles to the axis of rotation thereof, and means including a source of suitable potential connected to said electrode means for effecting discharge through the product moving along said path.

31. An electrical treating apparatus as claimed in claim 30 in which means are provided for rotating certain of the said electrode members in one direction and others in reversed direction.

32. An electrical discharge apparatus as claimed in claim 30 in which the electrode members have individually related thereto motive driving means therefor, the motive driving means of certain of said electrode members rotating them in one direction and the motive driving means of others driving them in reversed direction.

33. A double electrode structure for treating apparatus comprising, in combination, two substantially identical units each comprising a supporting arm to one side of which is rotatably supported an electrode member with driving motive means therefor, and means for securing said two arms together with the other sides thereof face to face.

34. An electrode structure as claimed in claim 33 in which the driving motive means for the two units are constructed to rotate normally in the same direction whereby, when said two units are secured together with the arms thereof face to face, one of said motive means is reversed end for end with respect to the other and the two electrodes are thereby driven in opposite directions.

45. 35. In an electrical treating apparatus, the combination of a discharge electrode above a treating zone and a plurality of conveyor rollers beneath said treatment zone, at least one of which is in the electrical circuit of the discharge and is adapted to serve as a discharge electrode to cooperate with the discharge electrode above the treatment zone for establishing a discharge therebetween.

55. 36. In an electrical treating apparatus, the combination of a discharge electrode above a treatment zone and a plurality of conveyor rollers beneath said treatment zone, at least one of said rollers having a conductive portion in the electrical circuit of the discharge and a solid dielectric means associated with the conductive means at the surface of the roller to form a capacity in series with the discharge and being adapted to serve as a discharge electrode to cooperate with the discharge electrode above the treatment zone for establishing a discharge therebetween.

70. 37. In an electrical treating apparatus, the combination of a discharge electrode above a treatment zone and a plurality of rollers mounted beneath said treatment zone adapted movably to support material to be treated therein and at least one having a dielectric surface and conductive means within the dielectric surface whereby said roller is adapted to serve as a ca-

pacitative electrode to cooperate with the discharge electrode above the treatment zone, and an energizing circuit including the electrode above the treatment zone and the conductive means within the roller for establishing and maintaining a discharge.

38. In an electrical treating apparatus, the combination of a discharge electrode above a treatment zone and a plurality of conveyor rollers beneath said treatment zone at least one of which comprises a dielectric tube with conductive means therein, a conductive pivot at one end electrically connected to said conductive means, and support means in the discharge circuit electrically connected to said conductive pivot by an oilless conductive bearing.

39. In an electrical treating apparatus, a conveyor roll adapted to serve also as a capacitative electrode which comprises a tube of dielectric material, conductive means within said tube, and at least one conductive pivot electrically connected to the conductive means within the tube.

40. In an electrical treating apparatus, spaced electrodes for a discharge one of which is movable and has a surface which is convex at the discharge area thereof and substantially continuous along the path of travel, and means for moving the surface of the electrode without changing its effective shape within the discharge area.

41. In an electrical treating apparatus, spaced electrodes for a discharge, one of said electrodes having a discharge surface which is substantially circular and mounted with its axis transverse to the direction of the discharge therefrom, and means for rotating said electrode about its axis.

42. In an electrical treating apparatus in which a product to be treated is subjected to a discharge resulting from impressing a high potential across two sets of electrode elements, the combination of, a tubular roller of dielectric material, a conductor within said roller, and an elongated condenser element electrically connected with said conductor and mechanically connected to one end of said roller.

43. In electrical treating apparatus, the combination of, a tubular roller of dielectric material, means to drive said roller, and a conductor element positioned in said roller, said means to drive said rollers including a belt of dielectric material.

44. In electrical treating apparatus, the combination of, a plurality of electrode rollers and a toroidal electrode structure positioned in operative relationship with respect to said plurality of electrode rollers, each of said electrode rollers having an individual electrode element associated therewith and cooperating with said toroidal electrode structure.

45. In electrical apparatus in which a product to be treated is subjected to a discharge resulting from impressing a high potential across a pair of electrode structures, an electrode structure comprising a plurality of electrode units, each of said units having an elongated shell of dielectric material and an elongated electrode with an effective discharge portion within said shell.

46. In electrical apparatus in which a product to be treated is subjected to a discharge resulting from impressing a high potential across a pair of electrode structures, an electrode-roller and condenser construction comprising a plurality of electrode-roller condenser units, wherein in each of said units is provided with a condenser

- means and an electrical conducting means, said conducting means having a portion adjacent the treatment zone but separated therefrom by an insulating means of solid dielectric material and 5 having another portion extending to a point remote from said treatment zone and electrically connected to said condenser means.
47. In electrical apparatus in which a product to be treated is subjected to a discharge resulting from impressing a high potential across a pair of electrode structures, an electrode structure comprising a plurality of elongated electrode-roller units positioned in parallel relationship and in a plane parallel to the plane of movement of the material being treated, each of said electrode-roller units having an electrical conducting means and an insulating means of solid dielectric material covering said electrical conducting means.
- 10 48. In electrical treating apparatus, a condenser construction composed of a pair of condenser structures positioned in cooperating relationship, one of said condenser structures in-

cluding an elongated element which is provided with dielectric shields, and the other of said condenser structures comprising a single flat metallic plate.

49. In electrical treating apparatus, a condenser construction composed of a pair of condenser structures positioned in cooperating relationship, one of said condenser structures comprising a plurality of elongated condenser elements, each of said elements having static shields 10 at its ends and a socket which is adapted to provide a pivot support.

50. In electrical treating apparatus, means to support a product being treated including, a conveyor roller adapted to serve as a capacitative 15 electrode formed by a tube of dielectric material having conductive means therein and having a conductive pivot electrically connected to the conductive means within said tube, a condenser element supporting said pivot and electrically 20 connected therewith, and a dielectric means supporting said condenser element.

FRANKLIN S. SMITH.

CERTIFICATE OF CORRECTION.

Patent No. 2,132,707.

October 11, 1938.

FRANKLIN S. SMITH.

It is hereby certified that error appears in the printed specification of the above numbered patent requiring correction as follows: Page 12, first column, line 31, claim 17, for the claim reference numeral "16" read 11; page 13, first column, line 48, claim 35, for the word "treating" read treatment; and that the said Letters Patent should be read with this correction therein that the same may conform to the record of the case in the Patent Office.

Signed and sealed this 24th day of January, A.D. 1939.

Henry Van Arsdale

(Seal)

Acting Commissioner of Patents.
